UNITED STATES PATENT OFFICE

171,277

PLASTIC TABLE MAT OR SIMILAR ARTICLE

Norman Forrest, New York, N. Y.

Application February 17, 1953, Serial No. 23,658

Term of patent 3½ years

(CL. D92—26)

To all whom it may concern:

Be it known that I, Norman Forrest, a citizen of the United States of America, residing in New York, county of New York, and State of New York, have invented a new, original, and ornamental Design for a Plastic Table Mat or Similar Article, of which the following is a specification, reference being had to the accompanying drawing, forming part thereof,

Fig. 1 is a plan view of a plastic table mat or similar article, showing my new design; and

Fig. 2 is a cross-sectional view thereof taken along lines 2—2 of Fig. 1.

I claim:

The ornamental design for a plastic table mat or similar article, substantially as shown.

NORMAN FORREST.
